DOOR LATCHING MECHANISM

Waldemar A. Endter, Long Beach, Calif.

Application April 23, 1949, Serial No. 89,173

20 Claims. (Cl. 292—198)

1

This invention has to do with improvements in lock and latch mechanisms of a type particularly adaptable to the fastening of automobile doors, and incorporating such features as door take-up action, and variously controllable locking and actuation from the inside and outside of the door.

Particularly the invention is directed to improvements in the structure and control of a keeper assembly adapted to be carried by the door and engageable with an appropriate pillar-mounted bolt device. In this connection the invention may be further characterized as pertaining to keeper mechanisms comprising spaced parts which receive between them the bolt assembly in an essentially dove-tail relation.

Considered in one of its major aspects, the invention has as one of its primary objectives the provision of a keeper mechanism presenting at the pillar opposed edge of the door a pair of spaced parts both movable in predetermined relation in the sequences of receiving between them the bolt assembly to secure the door, and in releasing movement under control of the door-carried operators to release the parts from the bolt to permit opening of the door. More specifically, I employ a pair of keeper parts movable relatively together for confinement of the bolt assembly between them so that one part supports the bolt assembly against the take-up thrust exerted against the other part, and movable apart to release the bolt assembly.

In the preferred form of the invention, the keeper parts both are mounted for pivotal or swinging movement, and are interconnected so that displacement of one is accompanied by corresponding displacement of the other. By locating such interconnection at the inside of the keeper mechanism housing or case, it becomes possible to control and actuate the positions and movements of the outside keeper parts by direct connection or association with the door-carried inside, outside, push button and key controlled operators. Briefly described, the keeper part control may be simply and effectively accomplished by application of the controls initiated by any of the operators, to or in association with the mechanism interconnecting the movable outside keeper parts, and generally in a manner such that in latched condition of the mechanism, the interconnection may be releasably held against bolt releasing movement, while for purposes of control, the operators may be thrown into and out of actuatable relation to the keeper parts.

All the various features and objects of the in-

2

vention, as well as the details of certain typical embodiments, will be explained and understood to best advantage in the following detailed description of the accompanying drawings, in which:

Fig. 1 is a view showing in elevation the pillar-opposed edge or face of the door, with the parts of the latch mechanism in the positions assumed when the door is open;

Fig. 2 is a side elevation of Fig. 1 as viewed from the left in the direction of the arrow 2;

Fig. 3 is a view similar to Fig. 1 showing the positions of the latch parts when engaged with the bolt assembly with the door closed;

Fig. 4 is a side elevation of Fig. 3 as viewed from the left in the direction of the arrow 4, with the added showing of the pillar and bolt parts carried thereby;

Fig. 5 is a perspective view showing the latch mechanism as viewed from the inside corner of the door, and with the parts having the positions assumed when the door is open;

Fig. 6 is a sectional view taken in the plane of line 6—6 of Fig. 5, with the parts in the positions assumed when the door is closed and the mechanism unlocked;

Fig. 6a is a fragmentary view showing certain of the parts in safety catch position;

Figs. 7 and 8 are views similar to Fig. 6 illustrating the parts in further changed positions;

Fig. 9 is a fragmentary enlarged section taken on line 9—9 of Fig. 7;

Fig. 10 is an enlarged fragmentary section taken on line 10—10 of Figs. 1 and 8.

Referring first to the general showing of Fig. 5, the automobile door structure, generally indicated at 10, may be of the usual form comprising an outside wall 11, to the edge flange 11a of which is applied the rubber cushion 12, a spaced inner wall 13, and the end or edge wall 14 which closes in opposing relation to the usual frame or pillar 15 appearing in Fig. 4. The latch and locking mechanisms, generally indicated at 16, are carried by an angular body or case 17, flange 18 of which is applied to the end wall 14 of the door as by screws 20, and flange 19 to its inside wall 13.

As best illustrated in Figs. 1 to 4, the latch mechanism includes a door-carried keeper assembly 21 comprising a pair of vertically spaced parts 22 and 23 movably mounted at the outside of the door face 14 for reception between them of the later described pillar-carried bolt assembly 24. The lower keeper part 22, mounted for vertical swinging movement about the pivot 25 and in a plane parallel to the door face, is shown to have

a bolt-engaging curved end surface 26 and a top surface 27 curved substantially as indicated and meeting surface 26 at the nose 28. The keeper part 23 may have the form of a segment or arm mounted for pivotal movement on pin 29 and having a straight flange edge portion 30 engageable with the bolt assembly 24 as will now appear.

It will be understood that insofar as the essential subject matter of the present invention is concerned, the door-carried latch mechanism may be used in conjunction with any suitable type of pillar-carried bolt or bolt assembly. Merely as illustrative, I have indicated at 24 a bolt assembly of the character described in my copending application Ser. No. 81,547, now Patent No. 2,606,784, dated August 12, 1952, entitled Vehicle Door Latch Mechanism, which for present purposes may be characterized as a type comprising a housing 31, the base 32 of which is stationarily secured to the pillar 15, the housing containing a bolt 33 mounted for swinging movement and engageable with the top face 27 of the keeper part 22. As fully explained in my copending application, the bolt may be mounted in its housing 31 for both bodily and swinging movements, and is so actuated as to exert against the keeper part 22 a thrust giving the entire mechanism a take-up action tending to crowd the door toward fully closed position along or against the pillar. The position of the bolt assembly between the keeper parts with the door fully latched, is shown by the broken lines at 34 in Fig. 3. As illustrated, flange 30 of the upper keeper part 23 is engageable against the top surface of the bolt housing 31, thus functioning as a support or abutment and forming with the lower keeper part 22 in the position of Fig. 3, a dove-tail arrangement confining the bolt assembly in its latched positions.

Referring now to Fig. 5, the keeper part 22 carries a pin 35 projecting through slot 36 in the door face and case flange 18, to connect with link 361 at the inside. This link in turn is pivotally connected by pin 37 with a crank piece 38 rotatable on the pin or shaft 29. With the keeper part 23 and crank piece 38 fixed to the shaft 29, link 361 serves to so interconnect these parts with the lower keeper element 22 that the outside keeper parts 22 and 23 rotate together between their open and closed positions of Figs. 1 and 3.

The keeper part 23 carries a pin 40 extending inwardly through arcuate slot 41 and carrying at the inside a pivoted pawl 42, the end 43 of which is engageable within notch 44 in the crank piece 38, and in a different position of the parts, against the safety catch shoulder 45. The pawl 42 is urged against the crank piece by a coil spring 46 carried by shaft 29 and bearing at 47 against the pawl. The pawl is carried bodily with the keeper part 23 during its rotational movements, but is capable of assuming different pivotal positions with relation to the crank piece 38.

The keeper control mechanism includes a toggle type linkage 47 comprising a lower arm or link 48 pivotally carried by pin 49 and having toward the case flange 19 an end shoulder or lug 50. Link 48 carries a pin 51 projecting through slot 52 in a second link 53 which in turn is pivotally attached at 54 to one end of a lever 55 pivotally fulcrummed on the post 56. Thus assuming lever 55 to remain in the same position, the links 48 and 53 are relatively movable by reason of their pin and slot connection 51, 52 between the posi-

tions shown in Figs. 6 and 8. Additionally, the links are capable of relative movement permitting elevation of the link 53, as from the position of Fig. 6 to that of Fig. 7.

The toggle link 48 and lever 55 are controllable by vertically reciprocable plate 58 paralleling the case flange 19, the plate being guided by the case-carried pin 59 extending through slot 60, and by confinement of the lower end of the plate within the guide piece 61. Plate 58 is vertically reciprocable between the positions of Figs. 5 and 7 through a suitable connection 63 with the usual push button (not shown) at the inside of the door. Such reciprocation of the plate rotates the lever 55 and moves link 53 between its Fig. 5 and Fig. 7 positions, by reason of the reception of the end of the lever within the plate opening 64.

Plate 58 also is shiftable vertically by key 20 operation of the mechanism from the outside of the door, as for example through key controlled rotation of the shaft 64 extending from the tumbler barrel 65, the shaft carrying on its inner end a fixed arm 66 received within the plate 25 notch 67 so that the plate responds in up and down movement to rotation of the shaft and arm.

The toggle link 48, and through it the upper link 53 are actuatable by the usual inside door 30 handle (not shown) connected by link 68 with lever 69 pivoted at 70 to the case flange and having an arm 71 engageable against the link 35 shoulder or lug 50. The toggle linkage is also 40 actuatable by way of an appropriate operator at the outside of the door, and shown typically as being of a push button type. The outside operator, generally indicated at 72, is shown to comprise a handle body 73 containing a push button 74, the rod extension 75 of which is engageable 45 against flange 76 of the link 48 to shift the toggle assembly from its Fig. 5 position to that appearing in Fig. 8.

In considering the operation of the mechanism, we may assume first the door to be in open position with the keeper and all associated door-carried parts to have the positions illustrated in 45 Figs. 1 and 5. It will be noted that the keeper part 23 is swung down directly into the path of the bolt housing 31 and that the bolt 33 itself 50 may have an elevation at or near the keeper surface 27. As the door is closed from the Fig. 1 to Fig. 3 position, flange 30 of the keeper part 23 is brought against the bolt housing 31, causing the keeper part to be swung upwardly and ultimately to the Fig. 3 position, the lower keeper 55 part 22 simultaneously swinging upwardly into confining relation with the bolt 33, by reason of the described connection between the keeper parts.

During these rotations of the keeper parts, the pawl 42, together with the engaged crank piece 38 are swung clockwise from the Fig. 5 to Fig. 6 position, in the latter of which the pawl is shown 60 to be brought upwardly and opposite surface 53a of the toggle link 53. The keeper parts may be released to permit opening of the door by actuation from either the outside or inside operators 65 76 and 68. In opening the door from the outside, advancement of the push button pin 75 against the toggle linkage results in movement of the link shoulder 53a against pawl 42 to release the latter from its engagement within the crank piece notch 44, whereupon the crank piece together with the keeper parts 22 and 23 are freed for restoration 70 to their Fig. 1, Fig. 5 positions, and consequent 75

disengageability from the bolt assembly. The same action results from actuation of the inside operator 68 to cause rotation of the toggle link 48 in a direction causing link 53 to bear against and free the pawl from the crank piece.

Assume next that it is desired to lock the keeper parts to prevent opening of the door from fully closed position. By depressing the push button rod 63, lever 55 is rotated to elevate link 53 a distance sufficient to bring its shoulder 53b, see Fig. 7, above the pawl 42, in which condition of the parts the pawl is unaffected by actuation of the toggle linkage 47 whether by either the inside or outside operators. The plate 58, lever 55 and link 53 are similarly shifted to the positions of Fig. 7, by rotation of the key controlled arm 66.

Provision is made whereby locked condition of the parts may be achieved under control of the outside operator and as a result of closing the door from open position. Assuming the door to be open, by advancement of the push button and rod 75, the toggle linkage 47 may be thrown to the Fig. 8 position in which the link shoulder 53b is first brought into the path to be taken by the pawl 42 as the door is closed. During its rotation, the end 42a of the pawl engages shoulder 53b, thus lifting link 53 to essentially the Fig. 7 position in which the toggle linkage is ineffective to actuate the pawl, and as a consequence of which the mechanism is locked until the toggle linkage is reconditioned by key shifting of plate 58, lever 55 and the link 53.

In considering now the safety catch operation of the mechanisms, it will be understood that as the door is swung toward closed position, the bolt 33, see Fig. 3, first will engage the outer end of the keeper part 22 and deflect upwardly to the point at which the keeper nose 28 is received within the bolt recess 33a. Such association of the parts thus establishes a safety catch relation restraining opening of the door from this so-called safety catch or incompletely closed position.

Finally assume the door to be fully closed and in unlocked condition as shown in Fig. 6, and that the linkage 47 is accidentally tripped to the point of temporarily releasing the pawl 42 from holding engagement with the part 38, but without the release being sufficiently sustained to permit full opening of the door in the manner previously explained. Upon initial release of the pawl from the Fig. 6 position, part 38 rotates counterclockwise and link 361 drops a distance limited as shown in Fig. 6a by engagement of its lug 80 with a turned stop flange 81 on the link 48. It is assumed that immediately upon the accidental tripping of the linkage 47, link 48 immediately will have returned to the Fig. 6a position in which the end 50 of the link engages against stop shoulder 82 to arrest swinging of the link under the influence of a coil spring 83 carried about pin 49, one end of the spring bearing against the case lug 84 and the opposite end against lug 85 carried by the link. Down travel of the link 361 thus is arrested at a location where the pawl claw 43 is positioned for engagement against shoulder 45 of member 38, thus establishing a safety catch relation for the reason that the bolt 33 is still confined between the keeper parts 22 and 23, and the latter will not be released to allow their full removal from the bolt assembly, until pawl 42 again is actuated by the linkage 47 to permit the parts to assume the condition shown in Fig. 7.

I claim:

1. A latch device comprising a supporting case, a keeper mechanism including a pair of vertically spaced parts mounted on and at the outside of said case to receive between them a bolt assembly, means mounting both of said parts for vertical movement relatively together and apart between bolt retaining and releasing positions, a pair of relatively movable elements at the inside of the case connecting said parts, said elements being movable together to bolt retaining positions as the keeper parts move from bolt-releasing to bolt-retaining positions, holding means maintaining said elements in their said bolt retaining positions, and means for releasing said holding means to permit bolt releasing movement of the keeper parts said parts being positioned for engagement of one of the parts by the bolt assembly with resultant relative movement of the parts apart while both parts simultaneously move upward.
2. A latch device comprising a supporting case, a keeper mechanism including a pair of vertically spaced parts mounted on and at the outside of said case to receive between them a bolt assembly, means mounting both of said parts for vertical movement relatively together and apart between bolt retaining and releasing positions, a pair of relatively movable elements at the inside of the case connecting said parts, said elements being movable together to bolt retaining positions as the keeper parts move from bolt-releasing to bolt-retaining positions, holding means bodily movable with one of the keeper parts and maintaining said elements in their said bolt retaining positions, and means for releasing said holding means to permit bolt releasing movement of the keeper parts said parts being positioned for engagement of one of the parts by the bolt assembly with resultant relative movement of the parts apart while both parts simultaneously move upward.
3. A latch device comprising a supporting case, a keeper mechanism including a pair of vertically spaced parts mounted on and at the outside of said case to receive between them a bolt assembly, means mounting both of said parts for vertical swinging movement relatively together and apart between bolt retaining and releasing positions, a crank piece rotatable at the inside of the case with a first one of said keeper parts, a link pivotally connecting said crank piece with the other of said keeper parts, a bodily movable pawl engaging and holding said crank piece, means mounting said pawl for movement with said first keeper part as the keeper parts swing from bolt-releasing to bolt-retaining positions, and manually operated means for releasing said pawl from holding engagement with the crank piece to permit bolt-releasing movement of the keeper parts said parts being positioned for engagement of one of the parts by the bolt assembly with resultant relative movement of the parts apart while both parts simultaneously move upward.

4. A latch device comprising a supporting case, a keeper mechanism including a pair of vertically spaced parts mounted on and at the outside of said case to receive between them a bolt assembly, means mounting both of said parts for vertical swinging movement relatively together and apart between bolt retaining and releasing positions, a crank piece rotatable at the inside of the case with a first one of said keeper parts, a link pivotally connecting said crank piece with

the other of said keeper parts, a bodily movable pawl engaging and holding said crank piece, means mounting said pawl for movement with said first keeper part as the keeper parts swing from bolt-releasing to bolt-retaining positions, and a manually controlled toggle linkage for releasing said pawl from holding engagement with the crank piece to permit bolt-releasing movement of the keeper parts said parts being positioned for engagement of one of the parts by the bolt assembly with resultant relative movement of the parts apart while both parts simultaneously move upward.

5. A latch device comprising a supporting case, a keeper mechanism including a pair of vertically spaced parts mounted on and at the outside of said case to receive between them a bolt assembly, means mounting both of said parts for vertical swinging movement relatively together and apart between bolt retaining and releasing positions, a crank piece rotatable at the inside of the case with a first one of said keeper parts, a link pivotally connecting said crank piece with the other of said keeper parts, a bodily movable pawl engaging and holding said crank piece, means mounting said pawl for movement with said first keeper part as the keeper parts swing from bolt-releasing to bolt-retaining positions, a second bodily movable and pivoted link engageable with said pawl to release the pawl from holding engagement with the crank piece to permit bolt-releasing movement of the keeper parts, said second link being shiftable to a position in which it is ineffective to so release the pawl said parts being positioned for engagement of one of the parts by the bolt assembly with resultant relative movement of the parts apart while both parts simultaneously move upward.

6. A latch device comprising a supporting case, a keeper mechanism including a pair of vertically spaced parts mounted on and at the outside of said case to receive between them a bolt assembly, means mounting both of said parts for vertical swinging movement relatively together and apart between bolt retaining and releasing positions, a crank piece rotatable at the inside of the case with a first one of said keeper parts, a link pivotally connecting said crank piece with the other of said keeper parts, a bodily movable pawl engaging and holding said crank piece, means mounting said pawl for movement with said first keeper part as the keeper parts swing from bolt-releasing to bolt-retaining positions, a pair of pivotally mounted control links one of which is bodily shiftable and engageable with said pawl, means connecting said control links for relative longitudinal and swinging movements, and means for actuating said control links to release said pawl from holding engagement with said crank piece, said pawl engaging control link being shiftable to a position in which it is ineffective to so release the pawl said parts being positioned for engagement of one of the parts by the bolt assembly with resultant relative movement of the parts apart while both parts simultaneously move upward.

7. A latch device comprising a keeper mechanism including a pair of spaced keeper parts adapted to receive between them a bolt assembly and both movable relatively together and apart between bolt retaining and releasing positions, a first of said parts having an inclined bolt engaging surface movable toward and away from the other keeper part, means interconnecting said parts so that engagement and movement of

one part by the bolt assembly moves the other part, said parts being positioned so that they move apart to receive the bolt assembly while simultaneously moving upward, movable holding means then acting to positively lock said keeper parts from movement apart and thus retain the bolt between the keeper parts, and an operator connected to said keeper mechanism and operable to release said holding means and allow release of the bolt from between said parts.

8. A latch device comprising a keeper mechanism including a pair of spaced keeper parts adapted to receive between them a bolt assembly and both movable relatively together and apart between bolt retaining and releasing positions, link means connecting said parts for movement together and bodily shiftable therewith, a first of said parts having an inclined bolt engaging surface movable toward and away from the other keeper part, said parts being positioned so that upon engagement of one of the parts by the bolt assembly both parts move apart to receive the bolt assembly while simultaneously moving upward movable holding means then acting to positively lock said keeper parts from movement apart and thus retain the bolt between the keeper parts, and an operator connected to said keeper mechanism and operable to release said holding means and allow release of the bolt from between said parts.

9. A latch device comprising a keeper mechanism including a pair of spaced keeper parts adapted to receive between them a bolt assembly and both movable relatively together and apart between bolt retaining and releasing positions, means mounting said parts for pivotal movement, a first of said parts having an inclined bolt engaging surface movable toward and away from the other keeper part, means interconnecting said parts so that engagement and movement of one part by the bolt assembly moves the other part, said parts being positioned so that they move apart to receive the bolt assembly while simultaneously moving upward, movable holding means acting to then positively lock said keeper parts from movement apart and thus retain the bolt between the keeper parts, and an operator connected to said keeper mechanism and operable to release said holding means and allow release of the bolt from between said parts.

10. A latch device comprising a keeper mechanism including a pair of spaced keeper parts adapted to receive between them a bolt assembly and both pivotally movable relatively together and apart between bolt retaining and releasing positions, link means connecting said parts for pivotal movement together and bodily shiftable therewith, a first of said parts having an inclined bolt engaging surface movable toward and away from the other keeper part, said parts being positioned so that upon engagement of one of the parts by the bolt assembly both parts move apart to receive the bolt assembly while simultaneously moving upward movable holding means positively locking said keeper parts from movement apart and thus retain the bolt between the keeper parts, and an operator connected to said keeper mechanism and operable to release said holding means and allow release of the bolt from between said parts.

11. A latch device comprising a keeper mechanism including a pair of spaced keeper parts adapted to receive between them a bolt assembly and both movable relatively together and

apart between bolt retaining and releasing positions, a first of said parts having an inclined bolt engaging surface movable toward and away from the other keeper part, means interconnecting said members for movement together, said parts being positioned so that upon engagement of one of the parts by the bolt assembly both parts move apart to receive the bolt assembly while simultaneously moving upward holding means cooperating with said connecting means, and including a locking device positively holding said parts in bolt retaining positions, and an operator actuatable to release said holding means.

12. A latch device comprising a supporting case, a keeper mechanism including a pair of vertically spaced parts mounted on and extending substantially parallel with the outside of a wall of said case to receive between them a bolt assembly, means mounting both of said parts for vertical movement relatively together and apart between bolt retaining and releasing positions, a first of said parts having an inclined bolt engaging surface movable toward and away from the other keeper part, means interconnecting said parts so that engagement and movement of one part by the bolt assembly moves the other part, said parts being positioned so that they move apart to receive the bolt assembly while simultaneously moving upward, movable holding means at the inside of said wall of the case then acting to positively lock said keeper parts from movement apart, and means operable to release said holding means and allow release of the bolt from between said parts.

13. A latch device comprising a supporting case, a keeper mechanism including a pair of vertically spaced parts mounted on and extending substantially parallel with the outside of a wall of said case to receive between them a bolt assembly, means mounting both of said parts for vertical movement relatively together and apart between bolt retaining and releasing positions, means at the inside of said case connecting said parts for movement together, a first of said parts having an inclined bolt engaging surface movable toward and away from the other keeper part, said parts being positioned so that upon engagement of one of the parts by the bolt assembly both parts move apart to receive the bolt assembly while simultaneously moving upward movable holding means at the inside of said wall of the case then acting to positively lock said keeper parts from movement apart, and means operable to release said holding means and allow release of the bolt from between said parts.

14. A latch device comprising a supporting case, a keeper mechanism including a pair of vertically spaced parts mounted on and at the outside of said case to receive between them a bolt assembly, the upper of said parts having a horizontally extending under bearing surface and the lower part having an inclined bolt engaging surface, means mounting both of said parts for vertical movement relatively together and apart between bolt retaining and releasing positions, means at the inside of said case connecting said parts for movement together, said parts being positioned so that upon engagement of one of the parts by the bolt assembly both parts move apart to receive the bolt assembly while simultaneously moving upward and manually releasable means cooperating with said connecting means and acting to then positively hold said parts against movement apart and in bolt retaining positions.

15. A latch device comprising a supporting case, a keeper mechanism including a pair of vertically spaced parts mounted on and at the outside of said case to receive between them a bolt assembly, one of said parts having an inclined bolt engaging surface and cooperating with the other part to hold the bolt in dove-tail relation, means mounting both of said parts for vertical movement relatively together and apart between bolt retaining and releasing positions, means at the inside of said case connecting said parts for movement together in one direction and releasable to permit bolt releasing movement of one part relative to the other, said parts being positioned so that upon engagement of one of the parts by the bolt assembly both parts move apart to receive the bolt assembly while simultaneously moving upward means then acting to positively hold said parts against bolt releasing movement apart, and means for manually actuating said connecting means.

16. The combination comprising a keeper mechanism including a pair of spaced keeper parts, means mounting said parts for movement relatively together and apart, and a bolt assembly comprising a housing and relatively movable bolt, said assembly being receivable between said keeper parts with the housing engaged against a first one keeper part and the bolt engaged against the other keeper part, means for moving both said keeper parts from a bolt assembly releasing position relatively together into a position in which they have dove-tail holding relation with said bolt assembly, holding mechanism for releasably holding the keeper parts in said position, and an operator actuatable to release the holding mechanism from said holding relation with the keeper parts to permit their movement apart to bolt assembly releasing positions.

17. The combination comprising a keeper mechanism including a pair of spaced keeper parts, means mounting said parts for movement relatively together and apart, and a bolt assembly comprising a housing and a relatively movable bolt, said assembly being receivable between said keeper parts with the housing engaged against a first one keeper part and the bolt engaged against the other keeper part, means for moving both said keeper parts relatively together into a position in which they have dove-tail holding relation with said bolt assembly by virtue of the engagement and movement of said first one of the keeper parts by said bolt housing, holding mechanism for releasably holding the keeper parts in said position, and an operator actuatable to release the holding mechanism from said holding relation with the keeper parts to permit their movement apart to bolt assembly releasing positions.

18. The combination comprising a keeper mechanism including a pair of spaced keeper parts, means mounting said parts for movement relatively together and apart, and a bolt assembly comprising a housing and relatively movable bolt, said assembly being receivable between said keeper parts with the housing engaged against a first one keeper part and the bolt engaged against the other keeper part, means for moving both said keeper parts relatively together by engagement by said assembly from assembly releasing positions to different positions in which they have dove-tail holding relation with said bolt assembly, the last mentioned means including a link interconnecting 75 said keeper parts for movement together, hold-

11

ing mechanism for releasably holding the keeper parts in said position, and an operator actuatable to release the holding mechanism from said holding relation with the keeper parts to permit their movement apart to bolt assembly releasing positions.

19. The combination comprising a keeper mechanism including a pair of spaced keeper parts both movable relatively together and apart, means mounting said keeper parts for pivotal swinging movement, and a bolt assembly comprising a housing and a relatively movable bolt, said assembly being receivable between said keeper parts by engagement and movement of one keeper part by the housing and overriding of the other keeper part by the bolt, means for moving both said keeper parts relatively together in response to movement of said assembly between them into a position in which they have dove-tail holding relation with said bolt assembly, holding mechanism for releasably holding the keeper parts in said position, and an operator actuatable to release the holding mechanism from said holding relation with the keeper parts to permit their movement apart to bolt assembly releasing positions.

20. The combination comprising a keeper mechanism including a pair of spaced keeper parts both movable relatively together and apart, means mounting said keeper parts for pivotal swinging movement, and a bolt assembly comprising a housing and a relatively movable bolt,

12

said assembly being receivable between said keeper parts with the housing engaged against a first one keeper part and the bolt engaged against the other keeper part, means for moving both said keeper parts relatively together into a holding position in which they have dove-tail holding relation with said bolt assembly by virtue of the engagement of said first one of the keeper parts by said bolt housing, said parts being positioned so that upon engagement of said first keeper part by the housing both parts move apart to receive the bolt while simultaneously moving upward, and a releasable holding mechanism positively maintaining the keeper parts against movement apart from their said holding position.
